UNITED STATES PATENT OFFICE.

FRIEDRICH WESTMEYER, OF ST. JOHANN, GERMANY.

STATIONARY BUFFER.

SPECIFICATION forming part of Letters Patent No. 630,577, dated August 8, 1899.

Application filed March 17, 1899. Serial No. 709,584. (No model.)

To all whom it may concern:

Be it known that I, FRIEDRICH WESTMEYER, a citizen of the Empire of Germany, residing at St. Johann-on-the-Saar, Germany, have invented certain new and useful Improvements 5 in Stationary Buffers, of which the following is a specification.

My invention relates to stationary buffers for railway-tracks, the object being to provide a device of this kind by means of which loads of iron beams or joists, rails, long wood beams and planks, or like materials which are moved beyond the head-walls of the wagon during transportation by the jerks and vibrations produced on the wagon may be readily brought again into their initial position suitable for transportation, thus avoiding loss of time and trouble due to the necessary transshipping of such loads.

The improvements consist in the construction, novel combination, and arrangement of parts fully described hereinafter and specifically pointed out in the appended claims.

In order that my invention may be the more readily understood and carried into practical effect, reference is hereby made to the accompanying illustrative drawings, in which—

Figure 1 is a side elevation of the improved stationary buffer with a portion of a truck 30 the load of which has been displaced by jerks or otherwise. Fig. 2 is a plan view of the buffer and truck shown in Fig. 1 and Fig. 3 is a view similar to that shown in Fig. 1 with the load of the truck brought again into its 35 proper original position.

In the drawings like letters refer to like parts throughout all the figures.

The improved stationary buffer consists principally of four uprights $a b c d$, preferably 40 made of old iron or steel rails and connected to each other by suitable cross-bars $x x$ and mounted on a foundation made of wood planks or stonework. In order to prevent the foot-rest h from contacting with or engaging the outer uprights a and d , the latter are curved inwardly at these points, as shown in Figs. 1 and 3. To the fore part of the uprights $a b c d$ is adjustably secured a strong plate e , 45 adapted to be adjusted to the respective height of the truck by means of suitable levers (not shown) or in any preferred way. Said plate serves as a rest to the load L of the truck.

The uprights $a b c d$ are strengthened by diagonal braces $a' b' c' d'$, connected to each other by cross-bars $x' x'$, and to said diagonal 55 braces are rigidly secured other uprights $a^2 b^2 c^2 d^2$, carrying the buffer-tie g . The position of the latter is such that the distance between the same and the rest-plate e is equal to the projection of the car or truck buffers 60 from the head-wall of said car or truck, so that said car or truck buffers engage said buffer-tie g after the displaced load has been moved again into its original position. This may be readily done by the aid of the locomotive, the latter pressing against the car or truck, whereby the load will engage said plate 65 e and be forced backward until the car or truck buffers are brought into contact with the buffer-tie g .

I would have it understood that I do not limit my invention to the particular form or arrangement of the construction herein shown and described, as it is evident that many changes in said construction may be resorted 70 to without departing from the spirit and scope of the invention. Thus instead of forming the various parts of the buffer apparatus of old iron or steel rails said parts may be constituted by solid wood beams or even any 75 suitable stonework, as desired.

Having fully described my invention, what I claim, and desire to secure by Letters Patent, is—

1. In a buffer for railway-cars, the combination with a backing or support, of a buffer carried thereby and adapted to be struck by a displaced load on the truck, and a second buffer arranged in rear of the first buffer so as to be struck by the truck-buffers after the 80 displaced load has come in contact with and been shifted by its buffer into proper position on the truck.

2. In a buffer for railway-cars, the combination with a backing or support and a plate supported thereby and adapted to be adjusted vertically and to form a buffer against which a displaced load on a car may be forced, of a buffer so located in rear of the said adjustable plate and its support as to be struck by buffers on the car after the load thereon has struck the adjustable buffer and been forced back into proper position on the car.

3. In a buffer for railway-cars the combi-

nation with a backing or support comprising uprights, certain ones of which are bent rearwardly for the purpose set forth, and a plate carried by said support and adapted to be struck by a displaced load on a car, and a second buffer located in rear of the backing and adapted to be struck by buffers on the car after the load thereon has struck the first buffer and been forced back into proper position on the car.

FRIEDRICH WESTMEYER.
